UNITED STATES PATENT OFFICE.

OSCAR KOPEL, OF NEW YORK, N. Y.

DESIGN FOR A SANDWICH TRAY.

Application filed March 18, 1926. Serial No. 16,973. Term of patent 7 years.

To all whom it may concern:

Be it known that I, OSCAR KOPEL, a citizen of the United States of America, and a resident of the city of New York, borough of Manhattan, in the county and State of New York, have invented a new, original, and ornamental Design for Sandwich Tray, of which the following is a specification.

Reference is to be had to the accompanying drawing in which—

Fig. 2 is a sectional view therethrough taken on the line 2—2 of Fig. 1.

I claim:

The ornamental design for a sandwich tray as shown.

OSCAR KOPEL.
